UNITED STATES PATENT OFFICE

JOSEPH A. FIRSCHING, OF UTICA, NEW YORK

AUXILIARY PRESSER-FOOT ATTACHMENT FOR SEWING MACHINES

Application filed June 16, 1927. Serial No. 199,367.

My invention relates to an auxiliary presser foot attachment for sewing machines and I declare the following to be a full, clear, concise and exact description thereof sufficient to enable anyone skilled in the art to which it appertains to make and use the same, reference being had to the accompanying drawings in which like reference characters refer to like parts throughout the specifications.

The object of the invention is to provide a sewing machine that is adapted to ruffle a narrow strip of fabric and at the same time sew it to another piece of fabric, which forms the body of the garment, and is run through the machine perfectly flat without any ruffle therein. To this end an auxiliary presser foot and separator plate is attached to the well known two feed sewing machine.

The fabric that is to be sewed without the ruffle therein is fed to the sewing machine over the separator plate, whereby it will not come in contact with the front feed mechanism of the machine and the edging strip is fed under the separator plate, whereby it will be acted upon by both feeds of the sewing machine with the resultant ruffle therein.

The invention may be found useful not only for the purpose of ruffling cloth but also it can be used in ruffling laces, ribbons, or any sort of fabric. Furthermore, it can be adjusted whereby to ruffle or merely full in the fabric. Several of the attachments can be fixed on one machine having a plurality of sets of feeds, whereby a plurality of edging strips can be sewed simultaneously to a piece of fabric.

The object will be understood by referring to the drawings in which

Fig. 1 is an elevational view showing the auxiliary presser foot and plate attachment applied to a differential feed sewing machine.

Fig. 2 is a detail perspective view of the attachment.

Fig. 3 is a plan view of a piece of fabric with the edging strip sewed thereto by means of the invention.

Fig. 4 is a detail perspective view of a bracket with shaft attached thereto employed.

Referring more particularly to the drawings, the parts of the sewing machine that are

old and well known in the art embody a cloth plate 1 disposed beneath the overhanging head member 2 carrying the vertically movable presser foot bar 3 to which is clamped at 4 the presser foot 5. Beneath presser foot 5 is the rear feed dog 6 that is adapted to reciprocate in two horizontal planes, an elevated plane as it moves forward, whereby to feed edging strip 10 towards the sewing mechanism and a lower plane as it returns, whereby to clear edging strip 10 for the purpose of securing a new hold thereon to feed it forward. There is also front feed dog 11, which reciprocates with a longer stroke than feed dog 6, although similar in all other respects. Because of this differential action in the length of stroke of feed dogs 6 and 11, edging strip 10 will be ruffled or fulled.

There is also the usual needle 15 carried by needle bar 16 which is reciprocated in a vertical plane. An aperture 17 is made in member 18 of presser foot 5, for the projection of needle 15. The parts that are new embody an auxiliary presser foot 20, which serves also as a separator plate that is formed with a depending part 21 at right angles to the horizontal part 22. The end 23 of horizontal part 22 is rounded off and is disposed just above front feed dog 11. A bearing or enlarged portion 24 is made integral with presser foot 20 and disposed at the apex and on the inner side of the angle between parts 21 and 22. An aperture 25 is made in bearing portion 24 for the projection of headed shaft 26. Ends of shaft 26 extend beyond the end surfaces of bearing portion 24. One of said ends is riveted in upstanding plate 27 made integral with bracket 30 that is screw bolted to cloth plate 1 at 31, 31. On the other end of shaft 26 is a collar 28 held in place by set bolt 29, whereby to aid in retaining shaft 26 in place. Shaft 26 has a loose fit in aperture 25 of bearing 24, whereby plate 20 will be permitted to rock thereon.

The presser part of plate 20 is formed at 35 by bending horizontal part 22 down at an angle at 36. Presser part 35 is disposed in a horizontal plane and is adapted to cooperate with front feed dog 11 in order to carry the edging strip 10 past the sewing mechanism.

The means for holding presser part 35 yieldingly against edging strip 10 as it is fed past the needle 15 embodies a coiled spring 40 disposed at one end about headed stud 41 which projects through an aperture in the depending part 21 of plate 20 and about threaded shaft 42 that is screw mounted to the frame 43 of the sewing machine. Shaft 42 projects laterally nearly through spring 40 leaving sufficient space between its free end and the adjacent end of stud 41 for plate 20 to rock. Adjustable lock nuts 45, 45 are mounted on threaded shaft 42, whereby to control the tension of spring 40.

15 It will be observed that the plate 18 of presser foot 5 is modified from the original, and is equipped with a novel upwardly inclined part at 51, whereby to provide a space at 53 therebelow for the disposition of auxiliary presser foot 20, as well as the manual feeding of fabric 55 to which strip 10 is to be sewed.

An adjustable plate 60 is pivoted at 61 to cloth plate 1 of the sewing machine. Plate 60 can be rocked on its pivot whereby edge 62 thereof can aid in determining the angle at which edging strip 10 will be fed to the sewing mechanism.

The operation of the device is effected by 30 feeding manually fabric 55 to the sewing mechanism into the space 53 between the lower surface of the inclined part 51 of rear presser foot 5 and the upper surface of auxiliary presser foot 20. Edging strip 10 will be fed manually also to the sewing mechanism up over edge 62 of plate 60 and onto plate 1 and under auxiliary presser foot 20.

When the sewing machine is in motion, rear feed dog 6 will by its reciprocatory motion 40 draw fabric 55 under the sewing mechanism without ruffling, gathering or fulling it. Said fabric 55 in this instance is subject only to the action of feed dog 6 because of the intervention of auxiliary presser foot 20 which separates said fabric 55 from the action of feed dog 11. Edging strip 10 on the other hand will be pressed into contact with front feed dog 11 by the yielding end of auxiliary presser foot 20, and into contact with 45 rear feed dog 6 by presser foot 5 whereby it will be subject to the differential actions of feed dogs 11 and 6 and hence be ruffled, gathered or fullled as shown in Fig. 3. As said fabric 55 and edging strip 10 pass under 50 needle 15 they will be sewed together resulting in the product illustrated in Fig. 3.

Having thus described my invention what I claim as new and desire to secure by Letters Patent is as follows:

60 1. In an auxiliary presser foot attachment for sewing machines having a differential feed, a presser foot for cooperating with one of said feeds, a rock member having parts disposed at right angles to each other for 65 cooperating with the other of said feeds, one

of said parts being bent to form a lower surface for cooperating with the second mentioned of said feeds, whereby a ruffled edging strip can be sewed to a piece of fabric without ruffling said piece of fabric, a bearing 70 formed at the angle of said parts of the rock member, a stud attached to said rock member, a shaft attached to said sewing machine, a coil spring surrounding said stud and shaft and means mounted on said shaft, whereby 75 to adjust the tension of said rock member.

2. In an auxiliary presser foot attachment for sewing machines having a differential feed, a presser foot for cooperating with one of said feeds, a rock member having parts 80 disposed at right angles to each other for cooperating with the other of said feeds, one of said parts being bent to form a lower surface for cooperating with the second mentioned of said feeds, whereby a ruffled edging 85 strip can be sewed to a piece of fabric without ruffling said piece of fabric, a bearing 90 formed at the angle of said parts of the rock member, a stud attached to said rock member, a shaft attached to said sewing machine, a coil spring surrounding said stud and shaft and lock nuts mounted on said shaft, whereby to adjust the tension of said rock member.

In testimony whereof I affix my signature.

JOSEPH A. FIRSCHING.
